OSCILLATOR

Max Geiger, Berlin, Germany, assignor to Telefunken Gesellschaft für Drahtlose Telegraphie m. b. H., Berlin, Germany, a corporation of Germany

Application June 8, 1937, Serial No. 146,986
In Germany June 16, 1936

7 Claims. (Cl. 250—36)

This invention relates in general to a relaxation oscillation generator.

A multivibrator is known to be a generator of relaxation oscillations in which two discharge paths are alternatively in action and whereby the one path puts the other one out of operation. Such relaxation oscillation generators can be utilized for the production of periodic electrical impulses employed in particular for purposes of television.

An object of my invention is to provide an oscillator which supplies a timing wave in which the impulses furnished by the multivibrator are rectangular in shape.

15 A further object of my invention is to provide means whereby the variation in anode current from the tubes of the multivibrator is substantially instantaneous.

Other features and advantages of my invention 20 will appear from the following description taken in connection with the accompanying drawing in which:

Fig. 1 is a schematic diagram of my improved multivibrator.

25 Figs. 2 and 4 show curves of the grid potentials of the multivibrator as hitherto demonstrated.

Fig. 3 shows the characteristic grid voltage-plate current curve for a tube such as used in a multivibrator.

30 Fig. 5 shows the plate potential curve for a multivibrator tube.

Referring now to Figure 1, those parts of the system which constitute a conventional multivibrator circuit will be explained. The multivibrator consists of discharge tubes 10 and 11, each of which includes a cathode, a control electrode and an anode. The cathodes of the tubes are connected together and are in turn connected to ground potential, whereas the anodes of each 35 of the tubes are maintained positive with respect to the cathodes by an appropriate source of potential, the positive terminal of which is connected to the anodes of the tubes 10 and 11 through the resistances 12 and 13 respectively. Connected 40 between the anode of each tube and ground is a resistance-condenser combination in order that the potential of the control electrodes of each of the tubes may be controlled. One plate of the condenser 14, for instance, is connected to the 45 anode of tube 11, the other plate of the condenser 14 being connected to ground by way of resistance 15. The control electrode of tube 10 is connected to the junction of the condenser 14 and the 50 resistance 15, this connection including a parallel 55 arrangement of a resistance 19 and a condenser

21. The purpose of the resistance 19 and the condenser 21 will become more apparent later. Likewise, one plate of condenser 16 is connected to the anode of tube 10, the other plate of the condenser being connected to ground by way of resistance 17. The control electrode of tube 11 is connected to the junction of the condenser 16 and the resistance 17, the connection including a resistance 20 in parallel with which is connected a condenser 22. The resistance 20 and the condenser 22 which are associated with tube 11 correspond to the resistance 19 and condenser 21 which are associated with the tube 10. These elements are not necessary so far as the multivibrator circuit and its operation is concerned, and, in order to explain the operation of the multivibrator system resistances 19 and 20, as well as the condenser 21 and 22, will be left out of consideration. There is also a certain inherent distributed anode-cathode capacity within each of the tubes 10 and 11, which are represented in the drawing and the presence of this capacity will also be ignored at present, for the purpose of explanation.

Figure 2 shows the pattern of the grid potential of the tube 10 (E_{g10}) as hitherto demonstrated for the multivibrator. In this figure, the pattern of the grid potential is shown as function of the time. In the point A the condenser 14 has a high charge such that its lower plate is negative with respect to its upper plate. The tube 10 has no current while plate current flows in tube 11. The potential at the lower plate of condenser 14 then varies in accordance with an e -function whose time constant is determined by the capacity 14 and the value of the resistor 15. In point B the voltage at the condenser 14 may be assumed to have decreased to such a degree that current also begins to flow in the tube 10. The horizontal dotted line in Figure 2 thus corresponds to the lower bend of the plate current-grid voltage characteristic of tube 10 as represented in Figure 3. As soon as a small plate current flows in the tube 10, the plate potential of 10 decreases because of the drop of the voltage at the resistor 12, and since the charge of the condenser 16 cannot change 40 suddenly, the grid potential of the tube 11 decreases at the same rate. This causes a decrease of the plate current of tube 11 and hence an increase of the plate potential of tube 11 in view of the reduction of the voltage drop through the resistor 13. This potential increase in turn has the effect that the grid potential of tube 10 increases still further, since also the charge of the condenser 14 cannot vary suddenly. In this manner there takes place alternatively an increase in the 45 50 55 60 65 70 75 80 85 90 95 100 105 110 115 120 125 130 135 140 145 150 155 160 165 170 175 180 185 190 195 200 205 210 215 220 grid potential of tube 10 and a decrease in the grid potential of tube 11, until grid current sets in in tube 10 and the plate current in tube 11 disappears completely. This condition corresponds to the point C in Figure 2. Now, the grid potential of tube 10 remains substantially constant until the charge on condenser 16 has disappeared to such a degree that current sets in again in tube 11. This condition corresponds to point 5 D in Fig. 2 and, at this time, the grid potential of tube 10 will be displaced in the negative direction because of the decreasing plate potential of the tube 11, causing a potential increase at the anode of the tube 10, and hence, also an increase of the 10 plate current of tube 11. In this way the plate current of tube 11 increases rapidly to a point in which the grid current sets in, while the plate current of tube 10 disappears completely. The condenser 14 has then again a high charge in the 15 sense of the plus-and-minus signs shown, so that the described performance repeats itself from point E in Figure 2. The pattern of the grid potential of tube 11 (E_{g11}) is shown in Figure 4.

Now it was to be expected that the pattern 20 of the plate potential of the two tubes would be absolutely rectangular, since it was believed that the plate current was always brought quickly to a constant value, while at the setting in of the discharge the plate current in the other tube 25 was likewise believed to fall to zero in a very rapid fashion. However, a closer investigation shows that this does in fact not occur. It is true that in point B in Figure 2, as above described, a plate current sets in in the tube 10 which increases rapidly also on account of the 30 feed back across the plate potential of tube 11. Therefore, also the potential at the anode of tube 11 increases rapidly at first, but the course 35 of the plate potential as a function of time is determined by the inherent cathode capacity 18 of tube 11 (and by other distributed capacities), as seen in the following. When the plate current of tube 11 decreases, the plate potential can only increase to the extent in which the 40 plate-cathode capacity 18 is charged through the resistor 13. This takes place with the time constant of the resistor 13 and condenser 18 which are both comparatively small, so that the plate potential of tube 11 first undergoes a steep 45 increase tending to adjust itself to the potential of the positive terminal of the battery in accordance with an e -function. The initial part of this e -function is designated by the portion F—G of the curve shown in Figure 5, the following part of which is shown in dotted line. 50 But, as already explained above, at an increase in the plate current of tube 10, a grid current also begins to flow very soon in tube 10 whereby the inner resistance of the grid cathode path is 55 very low. In other words this signifies that the small condenser 18 has the comparatively large condenser 14 practically placed in parallel thereto. At this point, therefore, the plate potential of tube 11 can now increase but very slowly instead of rapidly as desired, since the time constant is 60 a product whose one factor consists of the value of the resistor 13, and whose other factor consists of the sum of the capacity values of 14 and 18, and this time constant is considerably greater 65 than the time constant existing before the grid current in tube 10 sets in. Thus, the plate potential of tube 11 varies approximately in the manner represented by the portion G—H of the 70 curve shown in Figure 5 following the setting in 75

of the grid current in tube 10. This curve represents in fact an asymptote to the horizontal line representing the potential of the positive terminal of the battery, but this curve is produced with a much greater time constant.

It is therefore proposed in accordance with the invention, to insert resistors 19 and 20 respectively in the connection lines between the resistance-condenser members 14, 15 and 16, 17 and the connection terminals of the control grid. 10 These resistances have the effect that the time constant of the curve part G—H in Figure 5 will be increased to such a degree that, starting from the point G the plate potential can be considered as limited to the horizontal. (The 15 part F—G of the pattern of the plate potential has in fact a course that is still steeper than that shown in Figure 5.)

The resistors 19 and 20 completely fulfill the requirement to eliminate, in operation, the effect 20 of the parallel connection of the condenser 14 to the condenser 18, but eventually they may lead to an undesirable decrease in the steepness of the current increase of tube 10 and thus cause a slow current decrease in tube 11. The reason 25 for this can be found by the fact that the grid-cathode capacities of the amplifier tubes must, at an increase of their grid potentials, at first be charged across the resistors 19, 20 which can take place only with the time constant of the 30 grid resistance and grid-cathode capacity. The voltage at the grid-cathode capacity thus increases in accordance with a rectangular potential pattern, but at the anode of the other tube it increases only with a finite steepness. In order 35 to increase the rate of this increase of the grid potential the resistors 19, 20 may have condensers 21, 22 connected in parallel thereto. These condensers have the effect that at the control grids a voltage appears through capacitive voltage division between the parallel condensers 21, 22 and the grid-cathode capacities, which increases the plate current. The stationary condition lies in the fact that the potential increase at the anode of tube 11 will be 40 distributed in accordance with the relationship between the ohmic resistances 19 and 20 and the inner resistances of the grid-cathode paths when grid current flows. The transition from the capacitive to the ohmic voltage division takes place 45 in accordance with an e -function in the event that the inner resistance of the grid-cathode path can be considered constant as to time such as corresponds very favorably to the actual state at sufficient size of the condensers 21, 22. That 50 is, the time constant of the resistance and condenser 19, 21 and 20, 22 should be about the same as the time constant as caused by the grid-cathode resistance and capacity of the tubes 55 10 and 11.

Various modifications may be made in my invention without departing from the spirit and scope thereof and I desire, therefore, that only such limitations shall be placed thereon as are imposed by the prior art and are set forth in 60 the appended claims.

I claim as my invention:

1. A multivibrator for producing rectangular wave form comprising a pair of vacuum tubes each having a cathode, an anode and a control 70 grid, a condenser and a resistance connected in series between the anode and the cathode of each tube, a second resistance, said second resistance being connected between the control grid of one tube and the junction of the series condenser 75

and resistance of the other tube, means connected to each anode and cathode for maintaining said anodes positive with respect to said cathodes, and a resistance in each anode connection.

5. 2. In a relaxation generator, a pair of vacuum tubes each comprising a cathode, a control grid and an anode, a source of potential, circuit means for connecting said source of potential to said tubes to maintain the anodes positive with respect to the cathodes, a resistance in each anode circuit, a condenser and a resistance connected in series between the anode and the cathode of each tube, a conductor for connecting the control grid of each tube to the junction of the said condenser and resistance of the other tube, and a high resistance included in said conductor.

3. In a relaxation generator, a pair of vacuum tubes each comprising a cathode, a control grid and an anode, a source of potential, circuit means for connecting said source of potential to said tubes to maintain the anodes positive with respect to the cathodes, a resistance in each anode circuit, a condenser and a resistance connected in series between the anode and the cathode of each tube, a conductor for connecting the control grid of each tube to the junction of the said condenser and resistance of the other tube, a high resistance included in said conductor and a condenser in parallel with said high resistance.

20. 4. In a relaxation generator, a pair of vacuum tubes each comprising a cathode, a grid and an anode, a resistance connected to each anode and a source of current one terminal of which is connected to the cathodes and the other terminal of which is connected to the resistances, a condenser and a resistance connected in series between the anode and the cathode of each tube and a second resistance connected at one end to the grid of one tube and at the other end to the junction of the series condenser and resistance of the other tube.

5. 5. In a relaxation generator, a pair of vacuum tubes each comprising a cathode, a control grid and an anode, a resistance connected to each anode and a source of current one terminal of which is connected to the cathodes and the other terminal of which is connected to the resistances, means for connecting the anode of each tube to the grid of the other tube, said means including a condenser and a high resistance and a second resistance connected between the junction of said condenser and said high resistance and the cathode of each tube.

6. 6. In a relaxation generator, a pair of vacuum tubes each comprising a cathode, a control grid, and an anode, a resistance connected to each anode and a source of current one terminal of which is connected to the cathodes and the other terminal of which is connected to the resistances, a condenser and a resistance connected in series between the anode and the cathode of each tube and an impedance connected between the control grid of each tube and the junction of the series condenser and resistance of the other tube.

7. 7. In a relaxation generator, a pair of vacuum tubes each comprising a cathode, a control grid, and an anode, a resistance connected to each anode and a source of current one terminal of which is connected to the cathodes and the other terminal of which is connected to the resistances, a condenser and a resistance connected in series between the anode and the cathode of each tube and a time constant circuit connected between the control grid of each tube and the junction of the series condenser and resistance of the other tube, said time constant circuit being substantially equivalent to the time constant of the internal grid-cathode resistance and capacity of the associated tube.

MAX GEIGER. 40
